2 SHEETS—SHEET 2.

UNITED STATES PATENT OFFICE.

HERBERT R. SOCKWELL, OF PORT NORRIS, NEW JERSEY.

CLAM AND OYSTER DREDGE.

1,413,944.

Specification of Letters Patent. Patented Apr. 25, 1922.

Application filed March 14, 1921. Serial No. 452,137.

To all whom it may concern:

Be it known that HERBERT R. SOCKWELL, a citizen of the United States, residing at Port Norris, in the county of Cumberland and State of New Jersey, has invented certain new and useful Improvements in Clam and Oyster Dredges, of which the following is a specification.

My invention relates to improvements in clam and oyster dredges.

The principal object of my invention is to provide a dredge of the character stated, whereby the conformation of its structure and the distribution of weight therein is such as to cause said dredge to land on its teeth when cast from a boat into the water and then on its upward travel to turn the teeth away from said boat, thereby protecting both the boat and the teeth from injury; obviating the use of the unsatisfactory tooth guards now employed. A serious disadvantage of the tooth guard is that it has a tendency to ride the teeth out of engagement with the surface of the bed of the stream and in the conventional type of dredge a tooth guard is a necessity.

For the purpose of illustrating my invention I have shown in the accompanying drawings one form thereof which is at present preferred by me, since the same has been found in practice to give satisfactory results, although it is to be understood that the various instrumentalities of which my invention consists can be variously arranged and organized and that my invention is not limited to the precise arrangement and organization of these instrumentalities as herein shown and described.

In the drawings:

Figure 1 is a perspective view of the dredge as it is brought to the surface; or as it appears when about to be cast from the boat;

Figure 2 is likewise a perspective view of the dredge illustrating the same in operative position on the bed of the stream;

Figure 3 is an inverted plan view of Fig. 2; and

Figures 4, 5, 6, 7 and 8 are fragmentary detail views of various parts of the dredge, Fig. 4 being a plan view of the main frame at its point of connection with the chain from the brace bridging the arms 22 and 22'; Fig. 5 a plan view of the bowed end of the arms 22 and 22' and the brace bridging said arms; Fig. 6 a side elevational view of the

device at the point where the tooth bar is secured; Fig. 7 a plan view of the mud shoe and Fig. 8 a side elevational view illustrating a stanchion connecting an arm of the bag supporting frame with an arm of the main frame.

Like numerals of reference denote like parts throughout the drawings.

Referring to the drawings in detail and in particular to Fig. 2 thereof, the numeral 10 represents my improved dredge as an entirety; said dredge 10 being formed of a main frame 11, preferably constructed of metal, comprising a longitudinally extending yoke, substantially V shaped, the arms 11' and 11² thereof branching from an upwardly extending curved portion 12, forming one extremity of said frame 11. A clevis 13 is secured to the extending portion 12 of said frame 11, to which one end of the adjusting chain 14 is linked.

An adjustable or interchangeable mud shoe or weight 15 is bolted to the under side of the arms 11' and 11² adjacent and in front of a tooth bar 17 and bridges said arms 11' and 11². Adjacent said tooth bar 17, and to the rear thereof, a brace or weight 16 likewise bridges said arms 11' and 11² and is bolted to the upper side of said arms 11' and 11².

Said tooth bar 17 is also bolted to the upper side of said arms 11' and 11², between the mud shoe 15 and the brace 16. Teeth 18 are secured to the tooth bar 17 in the conventional manner.

A bag or net supporting frame 19 also branches from the portion 12 of the main frame 11 and comprises the arms 19' and 19², terminating in the semi-circular bows 95 or bends 19³ and 19⁴ bolted to the free ends of the arms 11' and 11², as illustrated.

Vertical extending stanchions 20 and 21, of graded heights, secured to the arms 11' and 11² and arms 19' and 19², assist in maintaining said arms 19' and 19² at a gradually inclined angle from said arms 11' and 11² of the main frame 11.

Inclined angular stanchions 23 are likewise secured to the arms 11' and 11² and arms 19' and 19². Obtuse angular braces 27 are provided between the stanchions 23 and the ends of the bows or bends 19³ and 19⁴ as shown particularly in Fig. 6, and angular braces 29, between the arms 11' and 11² and arms 19' and 19², are provided as shown in Figs. 1 and 2. The purpose of these various

stanchions and braces being to firmly maintain the frame 19 in a relative position with the main frame 11.

Arms 22 and 22' are bolted to the outer 5 sides of the angular inclined stanchions 23, slightly above the tooth bar 17 and extend longitudinally above the arms 11' and 11² and are curved upwardly and form a bow at their outer terminus above the like upwardly 10 extending curved portion 12 of the main frame 11.

A brace 22² bridging the arms 22 and 22' is provided just adjacent the bowed terminus of said arms 22 and 22' and to this brace 15 22² is linked the other end of the adjusting chain 14 as illustrated particularly in Fig. 5. A dragging chain 28 is linked to the bowed ends of the arms 22 and 22'.

A flexible S hood or ring bag or net 24 20 is attached to the bows or bends 19³ and 19⁴ of the arms 19' and 19² of the bag supporting frame 19, to the stanchions 23, the braces 27 and 29 and to a bar 30 which bridges the arms 11' and 11² adjacent and to the rear 25 of the tooth bar 17 to which it is secured by means of members 30'. S hooks 25 are employed to connect the links of said bag 24 to make it flexible. Weighted links 26 are provided on said bag 24, as illustrated, to 30 assist in keeping same submerged and in an open position.

The arms 11' and 11² are preferably constructed in rectangular form and the arms 19' and 19² and the arms 22 and 22' in 35 rounded form.

In use, the dredge 10 is cast from a boat, being in the position shown in Fig. 1 and connection is maintained therewith by means of the dragging chain 28. As the dredge 40 strikes the water, by reason of its conformation and the distribution of weight therein, as just described, it will turn forward on its teeth causing the said teeth to engage the bottom of the stream. Any length of tooth 45 may be used as the operator may require; the length of said teeth being determined by the depth of penetration of the bed of the stream requisite to secure the oysters or clams. It is necessary to penetrate the bed 50 of the stream to a greater depth for clams than for oysters, the latter usually lying on the surface of the bed of the stream while the clams ensconce themselves in the bed, especially if it be sandy.

55 The mud shoe 15 slopes toward the base thereof as particularly illustrated in Fig. 7 of the drawings, thereby permitting it to loosen or break up the surface of the bed or stream, ahead of the teeth 18, as the dredge 60 is dragged.

The dredge 10 is brought to the surface by means of suitable hoisting mechanism, on board the boat, secured to the chain 28 linked to the bowed end of the arms 22 and 22'.

65 The upward movement of the arms 22 and

22' will cause the main frame 11, carrying the tooth bar 17, teeth 18 thereon, and the bag supporting frame 19 integral with said main frame 11, to turn over and reverse its position by reason that the said arms 22 70 and 22', at their inner terminals, are secured to the angular braces 23 adjacent their connections with the arms 11' and 11² of said main frame 11, substantially, at and over the point where the said tooth bar 17 bridges 75 said arms 11' and 11² adjacent their inner terminals, and that the curved portion 12 forming the outer extremity of the main frame 11 is connected to and beneath the bowed end of the arms 22 and 22' by the 80 chain 14, secured to a brace 22² bridging said arms adjacent the outer or bowed end thereof.

As the chain 28 is drawn upwardly the dredge 10 gradually assumes a perpendicular position and the main frame 11 is drawn forwardly and upwardly at its inner terminal by the arms 22 and 22'. The said upward movement of the chain 28 also causes a corresponding upward movement of the said 90 main frame 11 at its opposite end by reason of the curved outer end 12 thereof being connected with and below the bowed end of the arms 22 and 22' by the chain 14 as hereinabove described. Thus the main frame 11 95 is subjected to a forward and upward pull at its inner terminal, the point of greatest weight, and an upward pull at its outer terminal, and as the dredge 10 assumes a substantially vertical position, the greater 100 weight of the inner portion thereof will cause the outer portion to swing inwardly between the arms 22 and 22', and the teeth 18 will be restored to the position shown in Fig. 1, a portion of the bag supporting frame 105 first coming in contact with the side of the boat and remaining in contact therewith, thereby enabling the operator to bring the bag 24 to the boat to be unloaded of its catch without the teeth 18 catching on the 110 boat or interfering with the unloading, obviating injury to either the teeth or the boat. A tooth guard has been employed, positioned in front of the teeth, but in practice has been found unsatisfactory. 115

I do not restrict myself to the exact details of construction, combination and arrangement of parts herein set forth, it being obvious that minor variations thereof, not involving the exercise of invention may be 120 made by the skilled mechanic and such departure from what is herein described and claimed, not involving invention, I consider as within the scope and terms of my claims.

Having thus described my invention what 125 I claim as new and desire to secure by Letters Patent is:—

1. In a dredge of the class described, a main frame comprising a yoke with weighted longitudinally extending arms, a tooth 130

bar secured to and bridging said arms, adjacent their terminals, teeth secured thereto, a bag supporting frame, braces connecting said arms with said bag supporting frame, longitudinally extending arms secured to said braces, said arms curving upwardly and being connected at their outer ends, a chain connecting the yoke of the main frame to and beneath said connected ends of said arms and means secured to said connected ends of said arms to lower and raise said dredge, substantially as described.

2. In a dredge of the class described, a main frame, comprising a yoke with longitudinally extending arms, a bag supporting frame connected with said yoke and the ends of said arms, a tooth bar secured to and bridging said arms adjacent their terminals, teeth secured thereto, a weighted mud shoe secured to said arms adjacent and in front of said tooth bar, a weighted brace secured to said arms adjacent and in the rear of said tooth bar, braces connecting said arms, adjacent their terminals and above the said tooth bar, with the bag supporting frame, longitudinally extending arms secured to said braces adjacent their connections with the arms of the main frame, said arms curving upwardly and being connected at their outer ends, a chain connecting the yoke of the main frame to and beneath the said connected ends of said arms and means secured to said connected ends of said arms to lower

and raise said dredge, substantially as described. 35

3. In a dredge of the class described, a weighted main frame, comprising a yoke with longitudinally extending arms, a bag supporting frame connected with said yoke and the ends of said arms, a tooth bar secured to and bridging said arms adjacent their terminals, teeth secured thereto, braces connecting said arms, adjacent their terminals and above the said tooth bar, with the bag supporting frame, longitudinally extending arms secured to said braces adjacent their connections with the arms of the main frame, said arms curving upwardly and being connected at their outer ends, a chain connecting the yoke of the main frame to and beneath the said connected ends of said arms and means secured to said connected ends of said arms to raise said dredge, whereby the said main frame thereof is subjected to a forward and upward pull at its inner terminal, the point of greatest weight, and an upward pull at its outer terminal, so that as the ascending dredge assumes a substantially vertical position the greater weight of the inner portion of said main frame will cause the outer portion thereof to swing inwardly between said arms, substantially as described. 40 45 50 55 60

In testimony whereof I affix my signature.

HERBERT R. SOCKWELL.
